United States Patent Office

Des. 189,357
Patented Nov. 29, 1960

189,357

TABLE

Lyman E. Woodard, Owosso, Mich., assignor to Lee L.
Woodard Sons, Owosso, Mich., a co-partnership

Filed Oct. 12, 1959, Ser. No. 57,905

Term of patent 3½ years

(Cl. D33—14)

The figure is a perspective view of a table showing my design.

I claim:

The ornamental design for a table, substantially as shown.

References Cited in the file of this patent

Interiors, February 1957, p. 115, view No. 8, armchair.
Furniture Retailer & Furniture Age, November 1956,
p. 25, bottom left, table by Meadowcraft.
Hettick Cat. No. 73, 1955, page 1, left center, table,
No. K5080.